US0D1003643S

(12) **United States Design Patent** (10) **Patent No.:** **US D1,003,643 S**
(45) **Date of Patent:** **** Nov. 7, 2023**

(54) **INDUCTION COOKING APPARATUS**

(71) Applicant: **YO-KAI EXPRESS INC.**, Hayward, CA (US)

(72) Inventor: **Chih Hung Lin**, San Jose, CA (US)

(73) Assignee: **YO-KAI EXPRESS INC.**, Hayward, CA (US)

(**) Term: **15 Years**

(21) Appl. No.: **29/760,042**

(22) Filed: **Nov. 27, 2020**

(51) LOC (14) Cl. **07-01**

(52) U.S. Cl.

USPC **D7/309**; D7/311

(57) **CLAIM**

The ornamental design for an induction cooking apparatus, as shown and described.

DESCRIPTION

FIG. 1 is a perspective view of an induction cooking apparatus, showing my new design;

FIG. 2 is front elevation view of thereof;

FIG. 3 is a left-side elevation view thereof;

FIG. 4 is a right-side elevation view thereof;

FIG. 5 is a top plan view of thereof; and,

FIG. 6 is perspective view thereof.

The bottom view and the rear view are not claimed in the present design.

The broken lines in the drawings depict portions of the induction cooking apparatus that form no part of the claimed design.

1 Claim, 6 Drawing Sheets
